UNITED STATES PATENT OFFICE.

CHARLES TUCKFIELD, OF EAST MOLESEY, ENGLAND.

INTERNAL-COMBUSTION ENGINE.

Application filed January 13, 1927, Serial No. 160,957, and in Great Britain October 5, 1925.

This invention relates to internal combustion engines and has for its object to produce an engine having the efficiency of a supercharged unit without the attendant complications and whereby I dispense with blowers and their gearing troubles, and save all the weight of piston and other pumps and also the space they occupy, and which engine will give a considerably greater H. P. 5 output, or the same output with a much lighter engine. A further object of the invention is to obtain the same compression pressure at high altitudes as at sea level and to avoid loss of power and fuel caused by 10 weak compression.

According to this invention I employ a valve positioned in a transfer passage between a compression chamber, which may be the crank case, and a port or ports near 20 the end of the cylinder, which ports are uncovered by the piston at the end of its outward stroke, the valve being so constructed that it is subject on one side to the pressure in the cylinder, when the ports are open, 25 and subject on the other side to the atmosphere and a regulating spring, the spring normally holding the valve in such position that the transfer passage is open until the pressure in the cylinder overcomes the force 30 of the spring and atmospheric pressure to move the valve to close the transfer passage.

My invention will be clearly understood from the following description aided by the examples shown on the annexed drawings 35 in which:—

Figure 1 is a sectional elevation (more or less diagrammatic) of a four stroke engine constructed according to this invention.

Figure 2 is a detail view of a modified 40 construction of piston valve.

Figure 3 is a sectional elevation (diagrammatic) of a two stroke engine with a portion of a second cylinder and piston showing my invention applied. It is to be understood that, for sake of clearness, the second cylinder is shown at the side but in practice would be in front, that is to say, would have the piston rod connected to the same crank shaft as the first piston.

1 is the cylinder, 2 the piston, 3 the crank case, 4 the air inlet valve, 5 the fuel inlet valve and 6 the exhaust valve, all of which are of ordinary construction. In one embodiment of the invention a valve casing 7 50 is attached to the cylinder, which casing has a passageway 8 connected at one end with a

port or ports 9 arranged near the end of the cylinder 1 and adapted to be uncovered by the piston 2 when it reaches the end of its outward stroke. The other end of the passage way 8 is connected by a pipe 10 to the crank case 3. In the casing 7 is a passage 11 which extends transversely of the passage way 8 and is connected at one end to the passage 11 at another point by an opening 12. 60 The other end of the transverse passage 11 is open to the atmosphere.

In the transverse passage 11 is positioned the piston valve 13 abutting against a spring 14, the pressure of which can be adjusted by any suitable means, such as a screw cap 15. In the piston valve 13 is a port 16 which is normally so positioned as to put that portion of the passageway on one side of the transverse passage into communication with the part of the passageway on the opposite side of said passage. Such port may consist of a hole bored transversely of the piston valve 13 as shown in Figures 1 and 3 or may be in the form of a circular groove in the 80 periphery of the valve 13, as in Figure 2.

When the valve 13 is in its normal position the port 16 is in alignment with the passage way 8 so that the port 9 is open to the crank case 3 and the spring 14 is adjusted to the pressure required in the cylinder 1. In the case of four stroke engines as shown in Figure 1 the fuel inlet valve 5 is arranged to close a little earlier than is usual and the crank case 3 is made comparatively air-tight 90 so that on the upward movement of the piston 2 air will be drawn in through the non-return valve 4 and compressed in the crank case 3 on the outward stroke.

The operation of a four-stroke engine 95 (Figure 1) is as follows:—A rich mixture is introduced into the cylinder 1 through the fuel inlet valve 5 in the usual way. In the outward movement of the piston 2, just before the piston uncovers the port 9, the inlet valve 5 closes and on the further outward movement of the piston 2 the port 9 is uncovered and the air compressed in the crank case 3 by the outward movement of the piston passes through the pipe 10, passage 100 way 8 and port 9 into the cylinder 1 until the pressure above the piston valve 13 reaches the required pressure determined by the spring 14. Any increase of pressure beyond this point will, acting through the 110 opening 12 on the end of the piston valve 13 force said valve outwards against the

spring 14 and move the port 16 out of alignment with the passage way 8 and prevent the passage of any more air into the cylinder 1. At the end of the compression stroke of the piston, the fresh air, which has now mixed with the charge admitted through the valve 5, forms an explosive mixture, at either a higher compression pressure or filling a larger compression space at normal pressure, whichever system of supercharging is preferred.

By this means constant compression at varying altitudes, with its great fuel saving and extra speed, will be gained attained, since although the pressure in the crank case 3 may be high, the valve 13 will prevent the passage of any excess of air into the cylinder 1. This is all that is required for road and water locomotion, but where great heights are attained, such as in aeronautical machines, the spring 14 would be set according to the level at which the machine is to travel, or the spring may be adjusted by the apparatus set forth in Tuckfield's British Patent No. 129,663 and also in Tuckfield's British Patent No. 171,538. In the latter case the device can be attached to the valve case 7 so that the pressure of its expansion is added to the pressure of the spring 14.

If a multi-cylinder engine is used, each cylinder 1 should have its own air compression chamber in the main crank case and duplex pistons of a size proportioned to the extra air required may be used.

When each cylinder 1 has its own separate crank case or air compression chamber 3 every alternate stroke of the piston is a scavenge stroke and this will assist in effecting a further saving in fuel, so that it will be seen that by this system all the advantages of supercharging are gained practically without the addition of any weight, space or complications.

Where no scavenging stroke is employed the mixture might be introduced into the crank case 3 as well as the cylinder 1, but I prefer to use air in the former, because where no scavenging stroke is used one crank case 3 and valve 13 would provide supercharge for two cylinders, but it would require a three way cock and means for actuating it.

In applying the invention to a two stroke engine I preferably provide the usual inlet ports, but regulate the exhaust by a mechanically operated valve 6^a, as shown in Figure 3, the supercharging valve 13 acting in a similar manner to that already described in relation to a four stroke engine.

I may employ a cylinder of enlarged bore at its lower end and fitted with a suitable piston working in tandem with the main piston, in which case I may use air in both the crank case and in the enlarged part of the cylinder and mix it with fuel before it passes

through the regulating valve 13 on its way to the ports 9 in the cylinder 1.

I may, as shown in Figure 3, employ the enlarged end 1^a of one cylinder 1 as a pump for scavenging another cylinder and the crank case 3 for charging and super-charging, or vice-versa, in which case I employ cross-over pipes 17, 17 and non-return valves 18, 18 connecting the adjacent cylinders 1, 1^b.

18 is the carburettor.

In this construction it is necessary to enlarge the bore of only a small part of the cylinder in order to enable the engine to operate as a two-stroke engine and to have the same compression pressure at elevations of twenty thousand feet, or higher, as at sea-level, as well as to operate with light or heavy oils, and to prevent loss of power and fuel caused by weak compression in heavy vehicles such as lorries, omnibuses and touring cars.

It will be seen that with this supercharger, not only is the risk of damaging gearing, which so frequently occurs in blowing superchargers (caused by the enormous velocity required of them), avoided, but also a large part of the power expended by them is saved.

With this system the unexpired compression is returned to the piston, that is to say, if only a small quantity of the supercharge is taken into the cylinder 1, the balance is left in the crank chamber 3 where it returns to the piston 2 the energy stored in it on its compression.

What I do claim as my invention and desire to obtain by Letters Patent is:—

1. An internal combustion supercharging engine comprising a cylinder having a port in its wall, a piston working in said cylinder and operable on its outer stroke to open said port, an air compression chamber connected to the outer end of said cylinder, a transfer passage between said compression chamber and said port, a valve controlling said transfer passage, and yieldable means tending to maintain said valve in open position to establish communication between said pressure chamber and said port, said valve having a portion subject to the pressure in said transfer passage for causing said valve to move into closed position when the pressure in the transfer passage is sufficient to overcome said yieldable means.

2. An internal combustion supercharging engine comprising a cylinder having a port in its wall, a piston working in said cylinder and adapted on its outer stroke to open said port, an air compression chamber connected to the outer end of said cylinder, a valve casing associated with said cylinder having a passageway connected at one end to said port and its other end connected to said compression chamber, said casing also having a

- passage open at one end to the atmosphere and extending transversely of said passageway and also having an opening between said passageway and the inner end of said transverse passage, a valve movable in said transverse passage having a port adapted to coincide with said passageway, said valve having its inner end subject through said opening to the pressure in said passageway, and having its outer end subject to the atmosphere, a spring acting on the atmosphere side of said valve to normally maintain its port in coincidence with said passageway, and means for adjusting the pressure of said spring on said valve.
3. An internal combustion supercharging engine, comprising a cylinder having inlet and exhaust valves adjacent its inner end and having its bore enlarged adjacent its outer end, that part of said cylinder of smaller bore having a port in its wall adjacent its outer end, means closing the outer end of that portion of said cylinder of larger bore, a duplex piston working in said cylinder and operable on its outer stroke to open said port and compress air in that part of the cylinder of larger bore, means comprising a non-return valve for admitting air to that part of the cylinder of larger bore, a conduit connecting that part of said cylinder of larger bore and said port, a valve controlling the passage of air through said conduit, yieldable means acting on said valve and normally holding it in open position, and means for adjusting the pressure of said yieldable means on said valve, said valve being subject to the pressure in said conduit and being movable into closed position when said pressure is sufficient to overcome said yieldable means.
4. An internal combustion supercharging engine comprising a cylinder having a port in its wall, a compression chamber connected to the outer end of said cylinder, a piston working in said cylinder operable on its outer stroke to compress air in said chamber and to open said port, a valve casing having a passageway connected on one side of said casing to said compression chamber and connected on the other side of said casing to said port, a valve movable in said casing for controlling the passage of air through said passageway, said casing having a passage through which atmospheric air may act upon said valve to assist in moving it into open position, yieldable means in said casing acting upon the atmosphere side of said valve and normally holding said valve in open position, said casing also having a second passage between said valve and said port through which pressure in said cylinder may act upon said valve and move it into closed position when such pressure is sufficient to overcome the pressure of the atmosphere and of said yieldable means upon said valve.

In testimony whereof I have hereunto set my hand.

CHARLES TUCKFIELD.
